(No Model.)

T. J. THORP.
CAR COUPLING IMPLEMENT.

No. 444,548.

Patented Jan. 13, 1891.

UNITED STATES PATENT OFFICE.

THOMAS J. THORP, OF CHICAGO, ILLINOIS, ASSIGNOR OF ONE-HALF TO
HENRY F. BAND, OF SAN FRANCISCO, CALIFORNIA.

CAR-CO尤LING IMPLEMENT.

SPECIFICATION forming part of Letters Patent No. 444,548, dated January 13, 1891.

Application filed June 14, 1890. Serial No. 355,440. (No model.)

To all whom it may concern:

Be it known that I, THOMAS J. THORP, a resident of Chicago, in the county of Cook and State of Illinois, have invented certain new and useful Improvements in Brakemen's Steel Couplers; and I do hereby declare the following to be a full, clear, and exact description of the invention, such as will enable others skilled in the art to which it pertains to make and use the same.

The object of the invention is to provide an implement for use in coupling cars. Brakemen are accustomed to some extent to use a short stick to manipulate the coupling-link, whereby they avoid exposure of their hands and diminish the danger of being crushed; but these sticks in practice are frequently mislaid, neglected, or splintered and rendered practically useless.

It is the design of the invention to provide a device that can be conveniently carried on the forearm without special attention, and so constructed that it can be instantaneously thrown into the hand into suitable position for use as a "stick" or extension-arm whereby to manage the coupling device of a car.

The invention consists in the parts and combinations hereinafter described and pointed out.

In the accompanying drawings, Figure 1 is a central longitudinal section of the device, the straps for securing it to the arm being omitted and the movement toward an operative position being indicated by dotted lines. Fig. 2 is a view on a smaller scale of a detachable cap provided with wings for the attachment of a securing strap or straps; and Fig. 3 is a view of the opposite end with the strap as arranged for securing the device to the arm.

Numeral 1 denotes a tube provided with devices of any convenient or suitable kind for attaching it to the forearm over the shirt-sleeve and preferably under the blouse or outer garment. In the present instance strips or wings 2 and 3, having suitable slots for the attachment of straps, are provided. As shown, the wings 3 are connected with a detachable cap 4, having a screw-thread connection with the main body of the tube 1. This is closed at its outer end, except for a

slot 5, through which extends a small steel bar 6. This bar is made of a size to loosely fit the slot, and both the slot and bar are preferably made angular, substantially as shown, 55 to prevent the rotation of the bar or rod.

7 indicates a head or piston on the bar, which fits loosely the interior of the tube.

8 denotes shoulders on the bar, adapted to act as stops and arrest the bar as it is passed 60 outwardly through slot 5.

It may be noted that the cap 4 turns readily on the tube, so that it adapts itself to the partial rotation of the wrist and does not interfere with the general use of the hand.

9 is a spring secured in the present instance to the cap 4 and arranged in the path of the movable bar 6, which is by preference bent at its end toward the spring to more certainly secure its engagement therewith, this form of 70 the bar being also very suitable for the use for which it is designed. The purpose of the spring is to prevent the incidental slipping of the bar in the tube, and it should not be stiff enough to materially oppose the throwing out 75 of the bar when its use is required. The particular form and location of this spring are not material, nor is its use, in fact, essential, as the same purpose could obviously be effected by friction.

10 denotes a cap closing the upper end of the tube. This is not essential, as the tube can be closed in any usual manner, the bar, with its head or piston, being capable of insertion at the end when cap 4 is removed, after which the latter can be slipped over the end of the bar and then connected with the main body of the tube.

The tube 1 having been secured in any convenient manner, as by straps, to the inside of 90 the forearm, with the bar concealed in its interior, the whole device will ordinarily be covered by the sleeve of the brakeman's blouse or coat, the spring or equivalent means preventing the rod slipping down by gravity through 95 slot 5.

When the brakeman has occasion to handle a coupling-link or to manipulate any part of a coupling device, the bar can be instantaneously thrown out into operative position by a 100 quick movement of the arm toward the position it must necessarily take for the work to

be done. No time is therefore lost, and the arm-extension is always available for immediate use. A quick reverse movement of the arm will return the bar to its hiding-place. It is obvious that the extremity of the bar can, if desired, be variously shaped for special uses or for particular kinds of car-couplers. The form illustrated is very suitable for the ordinary link-and-pin coupling commonly used on freight-cars; but I do not wish to be understood as limiting the invention in its details to the exact forms illustrated or the uses set forth, as they may be varied by mechanical skill without departing from the invention, so long as practically the same mechanical principles and construction are employed.

The increased security against accident afforded by the new device is apparent. It can be carried without discomfort or inconvenience and does not interfere with the ordinary use of the hands. It avoids the necessity of exposing a hand between the bumpers of cars or of putting the person in a dangerous position, as is the case when the coupling is done immediately by the hand, and it will when introduced into general use save many limbs and many lives.

It will be perceived that it is not necessary that the tube be cylindrical, nor that the wings have the particular location and form shown. They might, indeed, be omitted; but their use is preferred, as they hold the implement in place and afford a secure fulcrum for the device, acting as a lever. It is preferred to use steel nickel-plated, though this is not necessary, particularly for the tube.

I am aware that a coupling-tool has been supported by a leather sheath fitted to the hand, so that the coupling-rod was held below and alongside the hand, and also that a metal tube or case has been employed to hold a spring-actuated coupler-rod. In such prior coupling devices it has been necessary to pull the rod out of its sheath or case and to push it back, the rod being subject constantly to the tension of the spring; or in case the rod

was moved by a spring in one direction it was necessary to compress the spring to move it in a contrary direction, and a lock or catch requiring separate manipulation was necessary. Furthermore, such prior devices were not adapted to be secured and concealed under the sleeve or entirely away from the hand, nor could the coupling-rod be thrown by a simple movement of the forearm into or out of the hand.

It is characteristic of my improvement that the coupler, when not in use, is held entirely above and out of the way of the hand, and that the rod can be easily thrown into the palm or returned to its case, the retaining-spring being pushed aside by the momentum of the rod and exerting no pressure thereon, except near the beginning of its outward and the end of its inward movement.

Having thus described my invention, what I desire to secure by Letters Patent is—

1. In a car-coupling device, the combination of a tube or case, devices adapted to secure it to the front of the forearm above the hand and in a line passing near the longitudinal center of the palm, and a rod movable in said case and adapted to be thrown from and returned to the case by a movement of the arm, substantially as set forth.
2. In a car-coupling device, the combination of a tube or case, devices adapted to secure it to the front of the forearm above the hand and in a line passing near the longitudinal center of the palm, a rod movable in said case and adapted to be thrown from and returned to the case by a movement of the arm, and a retaining-spring only operative when the rod is near its retracted position within the case, substantially as set forth.

In testimony whereof I have signed this specification in the presence of two subscribing witnesses.

THOMAS J. THORP.
